UNITED STATES PATENT OFFICE.

WARREN M. BRINKERHOFF, OF AUBURN, NEW YORK.

PICTURE HOOK OR HANGER.

SPECIFICATION forming part of Letters Patent No. 371,665, dated October 18, 1887.

Application filed August 12, 1887. Serial No. 246,792. (No model.)

To all whom it may concern:

Be it known that I, WARREN M. BRINKERHOFF, a citizen of the United States, residing at Auburn, in the county of Cayuga and State of New York, have invented certain new and useful Improvements in Picture Hooks or Hangers; and I do hereby declare the following to be a full, clear, and exact description of the invention, such as will enable others skilled 5 in the art to which it appertains to make and use the same.

My invention is an improvement in picture-hangers, and has for its object to provide a hanger which can be made to adapt itself to 15 irregularities in the walls, to the irregularities of the supporting cornice or molding, also to permit of the hanging of a picture beneath the point at which two parts of the molding or cornice join, whether at some point on the side 20 walls or at the corners of the room, or at re-entrant angles within the room. It also has for its object the production of a hanger which may be attached to the walls by nails or screws at points where a solid bearing cannot be found 25 for a single nail or screw at a central point above the picture.

In the accompanying drawings I have shown several forms in which I have contemplated embodying my invention, and such invention 30 is fully disclosed in the accompanying specification and claims.

In the drawings, Figure 1 shows a form of my improved hanger with hooks for holding the cord in an inwardly-deflected position to 35 prevent the moving of the cord on its support and to retain the picture in position upon the walls. Fig. 2 shows a similar form of hanger with an additional picture-support on the connecting-bar. Fig. 3 is a view of a hanger 40 without the locking or retaining hooks. Fig. 4 is a view of a hanger designed to be supported by nails or screws. Fig. 5 is a view of a hanger similar to that shown in Fig. 1 with the end plates capable of adjustment toward 45 or from each other. Fig. 6 is a view of a modified form of adjustable hanger with a central picture-support added thereto. Figs. 7 and 8 are views of a hanger having the connection between the end plates of flexible

metal, said connection being corrugated to 5c give a greater degree of rigidity. Fig. 9 is a view of a hanger having a hinged or jointed connection between the two end plates. Figs. 10, 11, and 12 show hangers with other forms of adjustable connections between the end 55 plates.

Persons familiar with hanging pictures know that most walls are more or less irregular, which irregularities interfere with the proper hanging of pictures thereon. They are also aware 60 that it is not infrequently desired to hang pictures at points where the cornice is joined. In using nails or screws it is also a frequent occurrence that a solid support for the nail 65 cannot be obtained at the exact point at which it is desired to hang the picture and that the nail has to be driven at one side or the other of the desired point. I overcome these difficulties by my invention, and also provide a hanger which can be used for the support of 70 heavy pictures where an extended bearing upon the cornice is desired, although I do not claim, broadly, to be the first inventor of devices for accomplishing this result.

The general form of the hanger is much the 75 same in the various figures; and such hanger consists of two plates or arms, A A', provided with cord-supporting hooks or projections connected by a bar or rod, B. These plates or arms may be provided with cornice-hooks a, 80 as shown in nearly all of the figures, or may be provided with apertures a', to engage nails or screws or other supporting means, as shown in Fig. 4. The cord-supporting hooks or projections a' may be of the form shown, or of 85 any other preferred construction, and may be made integral with the plates A or attached thereto.

The bar B is preferably made of elastic or flexible material, so as to yield readily to the 90 irregularities of the wall or cornice. This degree of elasticity or flexibility in some cases may be sufficient to enable the hanger to be employed in corners of the room or upon re-entrant angles of the wall within the room. 95 In order that quite thin material may be used to form this connection and yet possess a sufficient degree of rigidity, such bar may be

stiffened at the points desired by corrugating the same or by providing it with elevated portions or depressions in a well-known way. Two forms of accomplishing this result are shown in Figs. 7 and 8. In the latter the corrugations extend inward from the outer ends, leaving a blank space in the center to afford greater facility for inward or outward deflection when desired.

10 In Fig. 5 the bar B is shown as extensible, being formed in two parts, b and b', overlapping each other, one of the parts being also provided with one or more hooks, b², on one side, forming a guide, which receives the end 15 of the other part, and in which such other part moves to effect the adjustment of the plates A the proper distance apart.

In Fig. 6 the bar B is formed in two parts, which engage similar guides on the back of a 20 plate, B', and the adjustment is secured in a similar manner. This plate B' may also be provided with cord-supporting hooks or projections a³ a³, from which another picture may be suspended.

25 In Fig. 10 I have shown the connection B as composed of two bars or rods, c c', which cross each other intermediate of such plates. These rods or bars are held by frictional contact in clips or bearings on the plates A, whereby a 30 certain amount of adjustment may be secured. In this case the plate B' is located at the point of the intersection or crossing of the rods or bars c c'.

35 In Fig. 11 the bar B is a single rod or tube connected with plates A in a similar manner, and the adjustment of the plates thereon is secured by moving them along such rod or tube.

40 In Fig. 12 the bar B is composed of one or more tubes, b, and one or more rods or tubes, b', of less diameter than the tube or tubes b, and which telescope within the same.

In Fig. 9 the bar B is formed of two parts, b b', hinged together at d.

45 In addition to the cord-supporting hooks, each hanger may be provided with hooks or projections e e, for holding the cord in an inwardly-deflected position, as shown in Figs. 1, 2, and 5. These hooks or projections may be 50 made from and form part of the bar B or the plates A, or may be attached to either of these parts.

The plate B' may be made of ornamental form, and may also be provided with cord retaining or locking hooks or projections e' e', as 55 shown in Fig. 2. This plate may be employed with each of the different forms of hanger shown, or it may be dispensed with and the hangers used without it.

60 The cord locking or retaining hooks e e on the hangers perform an additional function in a double hanger of this character, as by means of the same a considerable amount of outward strain is given to the lower end of the hanger, 65 and the cord, being locked or prevented from slipping on the cord-support, does away with

the tendency to draw the arms of the hanger together, and almost entirely relieves the connection between the arms from strain. Thus I am enabled to employ a connecting construction of light and flexible material, much lighter than could be used without them. 70

I do not desire to be limited to the exact constructions shown, as modifications of each may be made without departing from the principle 75 of my invention.

What I claim, and desire to secure by Letters Patent, is—

1. A picture-hanger consisting of two vertically-disposed arms, each provided with 80 means for engaging a support for the same, the said arms supporting the entire weight of the hanger, a connection between the said arms, and two independent cord-supporting projections below the supporting means, held from 85 contact with each other by the connection between the arms, substantially as described.

2. A picture-hanger consisting of two arms, each provided with means for engaging a support for the same, a connection between the 90 said arms holding the same apart, but permitting the independent adjustment of said arms, and a cord-support attached to said hanger, substantially as described.

3. A picture-hanger consisting of two arms, 95 each provided with means for engaging a support for the same, and a bar of flexible material connecting said parts and provided with elevations and depressions to increase the rigidity of the bar, and a cord-support attached 100 to said hanger, substantially as described.

4. A picture-hanger consisting of two arms, each provided with means for engaging a support for the same, and a bar connecting the 105 said arms, and an adjustable connection between said arms holding them from contact with each other, and a cord-support, substantially as described.

5. A picture-hanger consisting of two vertically-disposed arms, each provided with 110 means for engaging a support for the same, a bar connecting said arms and holding them out of contact with each other, and two cord-supports for two separate cords, substantially 115 as described.

6. A picture-hanger consisting of two vertically-disposed arms, each provided with means for engaging a support for the same, a connection between the said arms holding them out of contact with each other, a cord-support, 120 and locking or retaining projections below the cord-support for holding the cord in an inwardly-deflected position, substantially as described.

7. A picture-hanger consisting of two vertically-disposed arms, each provided with means for engaging a support for the same, a bar connecting said arms, a cord-support, and a plate attached to said bar and provided with an additional cord-support, substantially as 130 described.

8. A picture-hanger consisting of two ver-

tically disposed arms, each provided with means for engaging a support for the same, a connection between said arms, two cord-supports connected with the hanger, and a locking projection or projections below the cord-supports within vertical lines from the outer edges of such supports, substantially as described.

In testimony whereof I affix my signature in presence of two witnesses.

WARREN M. BRINKERHOFF.
